UNITED STATES PATENT OFFICE

DUDLEY CANFIELD, OF MILWAUKEE, WISCONSIN

TAKE-OFF DEVICE FOR AEROPLANES

Application filed November 26, 1928. Serial No. 321,902.

This invention relates to take-off devices for aeroplanes.

In aeroplanes, it is sometimes the case that the pilot has to rise within a very short distance in order to avoid obstructions. This limited space frequently precludes the possible take-off of the aeroplane and the machine has to be towed to a longer runway.

10 This invention is designed to overcome the defects noted, and to provide a novel form of take-off device which is so constructed that it permits the aeroplane to rise after a very short run, so that it may readily 15 clear obstructions in a limited runway and, therefore, which provides greater facility for taking off than has heretofore been possible.

Further objects are to provide a device 20 which is under the control of the operator although having automatic parts, and which is so constructed that the wheels or pontoons are shot downwardly from the machine, to thus suddenly elevate the machine and project it upwardly a distance from the ground 25 or water and thus aid materially in the shortening of the distance required for the initial run.

Further objects are to provide a device 30 having the characteristics noted above which does not impose an additional load upon the driving motors, but which operates wholly independently of the driving motors and through the agency of a landing and 35 take-off gear operated by an explosive device independently of the motor.

An embodiment of the invention is shown in the accompanying drawings in which:

Figure 1 is a side elevation of the aero-

40 plane showing it in its normal position;

Figure 2 is a view of the aeroplane just after it has taken off showing in dotted lines the path traversed by the center of the axle of the landing wheels;

45 Figure 3 is a fragmentary sectional view through one side of the take-off mechanism;

Figure 4 is a fragmentary view of the structure shown in Figure 3 taken at right angles to such figure;

50 Figure 5 is a sectional view through the

upper end of one of the take-off cylinders showing the valves in section.

Referring to the drawings, it will be seen that a conventional form of aeroplane body is indicated by the reference character 1. 55 This body is provided with braced hollow studs or struts 2 on opposite sides. These struts, in the usual construction of aeroplanes, carrying the landing gear, which may be either pneumatic wheels or pontoons. 60 For the sake of simplicity, wheels only have been shown, although it is to be distinctly understood that the invention is not limited to wheels but is also applicable to hydroplanes equipped with pontoons. 65

In this construction, the axle 3 for the landing wheels 4 is not carried directly by the bracing or struts 2, but is carried by means of vertical piston rods 5 located at 70 opposite sides of the machine, as is apparent from Figures 3 and 4. These piston rods extend upwardly through a fitting 6 secured to the frame-work of the machine. This fitting carries a compression spring 7 which normally is inactive, and merely loosely surrounds the piston rod 5. The upper end of the piston rod is rigidly attached to a piston 8 which slidably fits within the cylinders 9. The cylinders 9 will hereinafter be referred to as the take-off cylinders. 75

This construction is duplicated on opposite sides of the machine. The take-off cylinders 9 are provided with outlet ports 10 which communicate with an outlet channel 11 adjacent the lower end of the cylinder. 80 This outlet chamber or channel 11 is provided with a discharge pipe or exhaust pipe 12 which projects downwardly below the machine. 85

The cylinder is adapted to be supplied with compressed air and compressed gas or other fuel by means of the valves 13 and 14, respectively, hereinafter described in greater detail, and this explosive mixture is ignited by means of the spark plug 15. The 90 ignition of this mixture projects the pistons downwardly on opposite sides of the machine and thus suddenly forces the body of the machine upwardly, as the downward motion is resisted by the wheels contacting 95 100

with the ground. This downward motion of the piston continues until the pistons strike the springs 7 which act as cushions and relieve the shock of the blow.

5 The piston rods 5 are provided with lugs or cam members 16 which are engaged by the latches 17. These latches are urged towards locking position by means of the spring 18 (see Figure 3) and are adapted to 10 be released by means of the pull cords 19. These pull cords or tripping cords are under the control of the operator.

The detailed operation of the device will be given hereinafter.

15 The air inlet valve is provided with a casing formed of the members 20 and 21 (see Figure 5). The member 20 is screwed into the cylinder and the member 21 is bolted to the member 20. The member 20 is provided 20 with a valve seat adapted to be closed by the valve 22. This valve 22 is provided with a stem 23 guided in the member 21, as shown. Further, the stem carries a plate 24 against which a compression spring 25 bears, the 25 other end of the spring resting upon the member 20. The casing formed of the members 20 and 21 is supplied with compressed air through the medium of the compressed air pipe 26. This flow of compressed air is controlled by means of the valve 27 in the 30 compressed air line. The compressed air is drawn from any suitable source, for instance, the compressed air tank 28, (see Figure 2).

35 It is to be noted from reference to Figure 5 that a pipe 29 leads into the compressed air pipe 26 at a point beyond the valve 27. This pipe 29 communicates with a supply of lubricating oil, so that when the valve is 40 opened, the oil is sucked into the flowing stream of air and projected into the cylinder. Preferably, the valve 27 for each of the air pipes is provided with a lever 30 which is connected with an operating bar 31. This 45 operating bar joins the levers of the two valves and is under the control of the pilot.

The fuel inlet valve is provided with a casing formed of the inner member 32 screwed into the cylinder and provided with 50 a valve seat which cooperates with the valve 33. A second casing 34 is bolted to the casing 32 and a third casing 35 is secured to the casing 34. Within the casing 35 a sliding plunger 36 is positioned and is urged outwardly by means of the spring 37. This plunger is provided with a valve end 38 which cooperates with a valve seat formed 55 on the casing 34, as shown in Figure 5. The plunger is also provided with a screw threaded aperture into which the hollow stem 39 of the valve 33 projects. This hollow stem is provided with a plurality of apertures 40 for the escape of the pressure fuel.

60 65 It is to be noted also from Figure 5, that

a spring 41 urges the valve stem 39 outwardly towards valve closing position.

Within the plunger 36 a valve seat 42 is formed and is closed normally by the screw-threaded valve 43. This screw, threaded valve is held against axial shifting by means of the stationary member 44. It may be rotated to thus force the plunger 36 and the valve 33 downwardly or inwardly to the position shown in Figure 5. It may also be rotated in the opposite direction to permit the closing of the valve 33 and the opening of the valve 38.

The stem 43 is provided with a fuel aperture 45 which communicates with a fuel supply pipe 46 leading to a tank 47 adapted to contain the fuel under pressure.

The lever for rotating the valve stem 43 is indicated in Figure 3 by means of the reference character 48. These levers 48 are joined by means of a transverse rod, a portion of which is indicated by the reference character 49 in Figure 3.

The operation of the gas valve is as follows:

The levers 48 are rocked so as to rotate the screw threaded valve stem 43. This forces the plungers 36 inwardly and unseats the valves 33. Also, it moves the end of the valve stem 43 away from the valve seat 42 (see Figure 5) and thus allows fuel to pass through the radial apertures 50 into the space between the valve seat 42 and the valve 43. This fuel passes through the hollow valve stems 39 through the ports 40 and into the cylinder. The cylinder is previously supplied with compressed air by quickly opening the valves 27 and scavenging of the cylinders of burnt gases and filling them with fresh air. The fuel under pressure is thus projected into the cylinder and mixes with the fresh air.

This operation is performed while the machine is in flight and while the piston rods 5 are held down by the catches 17. When it is desired to land, the pilot pulls upon the cords 19, thus releasing the catches, and when the machine strikes the ground the wheels 4 transmit pressure upwardly through the piston rods 5 and force the pistons 8 into their uppermost positions, thus compressing the charge due to the weight of the machine.

When it is desired to again take off, the pilot starts the motors and when the motors have attained sufficient speed, he ignites the charges in the cylinders by closing the appropriate circuit and causing a spark at the plugs 15. This causes the sudden downward projection of the wheels which are in contact with the ground. The result is that the body of the machine is suddenly shot upwardly into an elevated position, as shown in Figure 2. At the downward stroke of the piston rods, the catches 17

again come into play and lock them in their lowermost positions. The pistons move past the ports 10 and allow discharge of the burnt gases. Scavenging is effected, as previously described, and the same cycle of operations is repeated.

It will be seen that a novel form of take-off device for aeroplanes has been provided which enables the pilot to take off with a 10 very much shorter run than has heretofore been possible, as means are provided for suddenly projecting the aeroplane bodily upwardly from the ground while it is in motion.

15 While the invention has been shown as applied to a land machine it is equally applicable to an hydroplane and, therefore, the term "wheels" or a similar expression appearing in the claim, is intended to cover 20 wheels, pontoons, or other landing elements.

25 Although the invention has been described in considerable detail, such description is intended as illustrative rather than limiting as the invention may be variously embodied and as the scope of such invention is to be determined as claimed.

I claim:

In an aeroplane, hollow struts extending downwardly, a supporting axle at the lower 30 end of the struts, piston rods connected to the axle adjacent the ends thereof, cylinders supported by the frame of the aeroplane having closed bottom walls, a piston connected to each piston rod and operating in 35 the cylinders, a coil spring at the closed end of each cylinder against which the piston abuts, a spring-pressed catch member adjacent each piston rod and a cam member carried by each rod for engagement by the 40 catch when the pistons are in the lower ends of the cylinders for retaining said piston rods in a projected position, and means for manually releasing the catch members whereby the tension of the springs in the 45 cylinders will cause the pistons to be returned to the opposite ends of the cylinders and return the axle to a normal position adjacent the lower ends of the struts.

50 In testimony that I claim the foregoing I have hereunto set my hand at Milwaukee, in the county of Milwaukee and State of Wisconsin.

DUDLEY CANFIELD.
